UNITED STATES PATENT OFFICE.

JOSEPH EARL LEONARD, OF SPRINGFIELD, MISSOURI.

COOKING-STOVE.

1,053,837.

Specification of Letters Patent. Patented Feb. 18, 1913.

Application filed November 12, 1910. Serial No. 591,954.

To all whom it may concern:

Be it known that I, JOSEPH E. LEONARD, a citizen of the United States, and a resident of Springfield, county of Greene, and 5 State of Missouri, have invented certain new and useful Improvements in Cooking-Stoves, of which the following is a specification.

My invention is an improvement in cooking stoves, and consists in certain novel constructions, and combinations of parts, hereinafter described and claimed.

The object of the invention is to provide a stove of the character specified having an oven arranged above the firebox and so constructed that the oven is ventilated and the heat evenly distributed throughout; a stove whereby a direct draft is heated to an intense heat before entering the fire from 10 below the firebox, and wherein a secondary draft is heated to an intense heat before being admitted above the bed of burning fuel.

Referring to the drawings forming a part 25 hereof: Figure 1 is a transverse vertical section of the improvement on the line 1—1 of Fig. 2; Fig. 2 is a similar view on the line 2—2 of Fig. 1; Fig. 3 is a section on the line 3—3 of Fig. 2; Fig. 4 is a top plan 30 view of the stove casing with the top removed, and Fig. 5 is a partial rear view of the stove casing.

In the embodiment of the invention shown in the drawings, the stove is composed of 35 sheet metal, and comprises a body casing 1, substantially rectangular in cross section, the lower edge of the casing being offset outwardly as shown at 2, to form a base. A bottom plate 3 is arranged transversely of 40 the casing above the offset portion, the said plate having its edges flanged at 4, and secured to the casing by rivets 5. An opening is provided in the front wall of the casing, the lower edge of the opening being at 45 approximately the level of the bottom plate, and a door 6 normally closes the opening. The door is hinged at its lower edge at 7 to the casing, and is provided with a suitable catch 8. The top 9 of the stove is of heavier 50 material as shown, and is provided with the usual openings covered by stove lids 10. The fire box 11 is formed by a bottom grate 12, a front plate 13, a back plate 14, and the usual end plates 15.

The back plate 14 is removable, the lower 55 edge sliding in a groove 16 in the rear bar of bottom grate, and the upper edge is laterally flanged at 17, and rests in a notch or rabbet 18 in a plate 19 arranged transversely of the casing a short distance below 60 the top 9 of the stove, to form, with the top and ends of the casing, a smoke passage 20. The front plate 13 and the end plates 15 of the fire box are also removable, and the former has a lateral flange 21 at its lower 65 edge which rests in a groove 22 in the front bar of the grate. The upper edge of the plate is also flanged laterally at 23, and the edge of the flange is received in a groove 24 at the front of the casing. Thus the plate 70 13, flanges 21 and 23 and adjoining casing side form air chamber C.

Adjacent to the flange 23, parallel to it and extending across plate 13 not to exceed length of fire box draft openings 26, 75 opening into air chamber C are provided, and in line with the upper face of the flange 23, a plate 27 is arranged, extending between extensions 28 of the ends of the casing. A door 29 is hinged to the free edge 80 of the plate 27 at 32, and closes against the top of the casing. The upper edge of the door is flanged laterally at 30, and the flange rests in a notch or rabbet 31 in the top. 85

A bracket 33 is secured to the door 29 near each end, and a hollow rod 34 extends between the brackets, forming a handle for opening and closing the door. The said door is the fire box door, through which 90 fuel is introduced. The door 6 is the ash pit door, and an ash pan 35 rests upon the bottom plate 3, adjacent to the door 6.

A baffle plate is arranged transversely of the casing at the rear thereof, the said plate 95 comprising a substantially rectangular portion 36, and a substantially vertical portion 37, the latter having its free edge forwardly curved at 38. The plate is held to the end walls of the casing by means of rivets 39, 100 passing through flanges 40 on the ends of the plate. The baffle plate is arranged with the portion 36 approximately parallel with the plate 19, and with the portion 37 approximately parallel with the back plate 14 105 of the fire box, and a second baffle plate 41 is secured to the front wall of the casing below the fire box, by means of rivets 42,

passing through a flange 43 on the plate. The plate 41 and the portion 38 of the plates 36—37 deflect and guide the ashes and cinders into the ash pan, and the plates 5 36—37—38 form with the plates 14 and 19, a conduit or passage for air to the fire box, the said passage communicating with the atmosphere through an opening 44, in the rear wall of the casing. The said passage 10 is the direct draft passage for the fire, and a draft door 45 is provided for the opening, and is hinged to the casing at 46, for regulating the draft through the passage. The passage 20 before mentioned communicates 15 by means of an elbow 47, with a pipe 48, extending vertically to the oven to be described.

The oven consists of a substantially rectangular casing 49 supported above the casing 1, by means of brackets 50, and the casing 49 is provided with an opening 51 in its top, encircled by a collar 52, and with an opening in its front, closed by a door 53, hinged by its lower edge at 54 to the casing, 25 and provided with a handle 55. Near the top and bottom of the oven, and spaced apart therefrom, plates 56 and 57 are arranged transversely of the casing. The ends of the said plates are spaced from the ends 30 of the oven, and are connected by end plates 58, thus forming a central compartment for containing the articles to be baked, and upper and lower compartments connected by end compartments or passages.

35 The lower compartment communicates with the pipe 48, and the upper compartment communicates with the flue, not shown, by means of the opening 51. The heated gases from the fire in the fire box pass 40 through the passages 20—47 and 48, to the lower compartment of the oven, thence by the end passages to the upper compartment and to the flue.

A baffle plate 70 is arranged below bottom 45 plate 57, said plate being arched downwardly, and having at its center a V-shaped extension to divide the heated gases and deflect them to each side of the oven. This plate is joined and secured to back oven 50 casing by rivets or bolts and its sides are curved outward and around the corners formed by the junction of plates 58 to plate 57, and back against plates 58 and are secured to the said plates 58 by rivets or bolts. 55 Front edge of plate 70 secured to front oven casing by means of groove provided therein. The plate 70 thus placed a short distance from and adjacent to plate 57 thus forms air passage *a*, said air passage being of 60 greatest depth at back and least depth at front and proportionately graduated between, owing to inclined construction of plate 70 from back to front. Air passage *a* connects to outside atmospheres by means

of small openings *b* in rear of oven casing, 65 and located in rear between plates 57 and 70. Each of the plates 58 is provided with a transverse series 59 of openings near its connection with the plate 57 and opening 70 into passage *a*, and the said plate 57 is provided with a similar series 60 near its front edge and also opening into passage *a*. The upper plate 56 is also provided with a similar series 61, near its rear edge and opening 75 into upper oven compartment. Air entering passage *a* through openings *b* is heated to an intense heat by coming in contact with plate 70 which in turn is heated by the hot gases entering lower oven compartment 80 from pipe 48, this air then travels forward and up into inner oven compartment through openings 59 and 60, on through oven as indicated by the arrows as shown in Fig. 1, and out top of oven through openings 61, thus distributing the heat and ventilating the oven. 85

The improved oven is supported in a position easily accessible without stooping, and the size of the oven is to a certain extent independent of the size of the stove, and 90 may be much larger proportionately than the stove. In addition, the oven constructed as above described, will heat uniformly since the intense heat of plate 70 is distributed throughout oven by means of the current of air and this current of superheated air thus ventilates the oven perfectly insuring more perfect and uniform baking. 95

When the draft door 45 is opened, the air entering comes into contact with the plate 100 19, and with the back plate 14, both of which are heated by the heated gases passing to the oven. The said air is thus intensely heated, reaching a temperature of 105 approximately 600° F. From a scientific and economic standpoint this feature is important. Since in the process of combustion, 110 the union of oxygen and carbon is more perfect and complete at higher temperatures, the combustion will thus be more complete than is ordinarily provided in ranges. In 115 the ordinary range, in which the outside air is admitted direct to the fire the first physical effect of the heat upon the air is its expansion and this necessarily takes place in the most confined space, namely, in the interstices of the fuel. Though the air is moving upward, this expansive force acts downward as well as other directions thus retarding the draft to a certain extent. In this 120 stove since the air is preheated its expansion upon entering the fire is less and thus a stronger draft is created. Also since the air is preheated the nitrogen associated with the oxygen and which is not a supporter of 125 combustion, thus abstracts less heat from the body of fuel and burning gases. Thus it results that from an equal amount of fuel

and an equal draft the temperature is much higher in the range in question than in an ordinary stove. In other words, the necessary temperature is obtained with a less 5 amount of fuel.

In addition to the direct draft, a secondary draft is provided. From an inspection of Figs. 2 and 4 it will be noticed that the plate 19 is curved transversely, being arranged with its concave face upwardly. A plate 62 is connected to each side edge of the plate 19, by means of rivets, as shown, and each of the said plates 62 curves outwardly and upwardly to a connection with the top 15 of the stove. Each of the said plates is also provided with a lateral extension 62^a extending laterally outward into engagement with the adjacent side of the casing 1. Each 20 of the said plates 62 and its extension forms with the casing a triangular passage 63, each of the said passages leading forwardly. The plates 62 and their extension 62^a extend from the rear of the casing 1 to the air chamber at the front of the stove, and the passages 25 63 permit air entering through openings 64 at the rear of the stove, to pass into the chamber C and from thence into the fire box above the fire. This draft also has many advantages both from a scientific and economic 30 standpoint. Since this air is heated to an intense heat of from 600 to 700 degrees F. before passing over the fire it readily combines with and creates combustion of the gases which are escaping from the bed of 35 fuel and which would otherwise escape up the chimney unburned. In burning coal these gases, which are greater in quantity when fresh fuel has been added, consist of carbonic acid and the different hydrocar- 40 bons which are easily combustible if the necessary amount of oxygen is admitted at the right temperature. Thus it is that by the use of this secondary preheated draft the waste gases are burned which means economy 45 of fuel, and almost perfect and smokeless combustion is obtained. Since this secondary preheated draft is constant it answers the above described purpose only when the bed of fuel is giving off the gases mentioned, 50 that is after the bed of fuel is coked; or in other words after all the gases are given off this secondary preheated draft answers the purpose of keeping up a continual hot draft across the bed of fuel, under the lids and 55 around the oven even if the direct preheated draft is closed and without burning a great amount of fuel. This draft also prevents the lids from overheating in proportion to the oven temperature as it tends to force the 60 heat around the oven which would otherwise be retained largely under the lids.

The stove casing 1 is provided with the usual side shelves 65, and the draft door 45 is provided with a handle 66 for operating

the same. Flue strips 67 are arranged in the 65 space below the baffle plate 70 of the oven, one on each side of the opening of the pipe 48, to deflect the heat frontward and upward. The said plates are of lesser height than the space, so that a portion of the gases 70 may pass over them.

The outer wall of the oven casing is preferably double, and sheets 68 of asbestos, or other heat non-conducting material, are arranged between the walls. Baffle plates 69 75 are also provided at the upper corners of the casing in the space between the top plate 56 and the top of the casing.

I claim:

1. A cooking stove comprising a casing 80 having a fire box, and a passage for the heated gases leading from the fire box beneath the top of the casing to the rear thereof, said casing having a draft passage leading to a point below the fire box and adapted 85 to communicate therewith, and having other draft passages leading to the front of the fire box and delivering over the burning fuel supported in the fire box, said passages being arranged one on each side of the first- 90 named passage and delivering at the ends of the fire box, and a draft door controlling the first-named draft passage.

2. A cooking stove comprising a casing 95 having a fire box, and a passage for the heated gases leading from the fire box beneath the top of the casing to the rear thereof, said casing having a draft passage leading to a point below the fire box and adapted to communicate therewith, and 100 having other draft passages leading to the front of the fire box and delivering over the burning fuel supported in the fire box, said passages being arranged one on each side of the first-named passage and 105 delivering at the ends of the fire box.

3. A stove comprising a casing provided with a fire box, and having a passage for the outlet gases leading from the fire box to the rear of the casing, and having a draft passage arranged directly below the passage for the outlet gases, and leading to a point below the grate of the fire box and communicating with the fire box through the grate, said 110 casing having other draft passages leading 115 from the rear of the stove to the front of the fire box and communicating with the fire box above the level of the fuel supported by the grate, one of said passages being arranged on each side of the passage for the 120 outlet gases, and a damper for controlling the first-named passage.

4. A stove comprising a casing provided with a fire box, and having a passage for the outlet gases leading from the fire box to the 12 rear of the casing, and having a draft passage arranged directly below the passage for the outlet gases, and leading to a point below

the grate of the fire box and communicating with the fire box through the grate, said casing having other draft passages leading from the rear of the stove to the front of the fire box and communicating with the fire box above the level of the fuel supported by the grate, one of said passages being ar-

ranged on each side of the passage for the outlet gases.
